Arthur D. Jenkins,

ATTORNEY.

UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

TERMINAL FOR ELECTRICAL PURPOSES.

1,378,201.

Specification of Letters Patent. Patented May 17, 1921.

Application filed February 16, 1918. Serial No. 217,682.

To all whom it may concern:

Be it known that I, ELMER B. STONE, a citizen of the United States, residing at New Britain, in the county of Hartford and 5 State of Connecticut, have invented a new and Improved Terminal for Electrical Purposes, of which the following is a specification.

My invention relates more especially to 10 the class of devices employed for removably attaching an electrical conductor in place, and an object of my invention, among others, is to provide a terminal that may be quickly and securely fastened at the end of an insulated wire in a manner to provide a very 15 efficient connection.

One form of device embodying my invention and in the construction and use of which the objects herein set out, as well as others, 20 may be attained, is illustrated in the accompanying drawings, in which—

Figure 1 is a view of a piece of insulated wire showing my improved terminal attached thereto, one end having the insulation 25 partly removed to illustrate the method of attachment.

Fig. 2 is a detail side view of my improved terminal.

Fig. 3 is a similar view but looking at the 30 opposite side of the terminal.

Fig. 4 is a view of one end of the wire with the insulation partially removed, said wire being arranged in a position at right angles to that shown at the right hand side 35 of Fig. 1.

Fig. 5 is an end view of a conductor having my improved terminal attached thereto.

My improved terminal is not restricted to use in connection with any particular form 40 of electrical conductor or to any particular use to which said conductors may be put, but as it finds ready application to short conductors that are intended to be removably secured at their ends to binding posts, I 45 have selected such for the purpose of illustrating my invention in the drawings herein, in which the numeral 5 indicates a short conductor having any suitable form of insulating material 6 comprising the outer portion 50 and surrounding a wire or conducting core 7. This insulating material is of such a nature that it may be penetrated by a sharp instrument and I make use of this feature as

a means of securing my improved terminal in place. 55

This terminal embodies a support that is embedded in the substance of the insulating material and that preferably is provided with means whereby it may be forced into said material. In its preferred form this 60 support comprises a short tube 8. This tube is formed from any suitable conducting material, as copper, and has preferably on its outer surface a thread 9. Its end 10 is more or less sharp to cause it to readily penetrate 65 the insulating material 6. One side of the tube 11, at that end opposite the sharpened end, is preferably longer than the opposite side, and a notch 12 is formed in this end to receive the wire 7. 70

An ear 13 preferably constituting a loop is formed integral with the tube or support 8, this ear preferably having an opening 14 extending lengthwise along the center thereof and to receive a binding post to which the 75 terminal may be attached.

In securing my improved terminal in place the ear 13 is grasped between the thumb and fore-finger and the sharpened edge 10 is placed against the end of the insulating material, with the wire 7 in the center. By turning the terminal in a direction to cause the thread 9 to draw the terminal into the insulating material, said terminal may be readily forced into place, and 80 as particularly shown in Fig. 1 of the drawings. When thus positioned it will be noted that the support is thoroughly embedded in the substance of the insulating material, there being a portion 15 of such substance 85 located between the wire and the support as well as a substantial part of the material outside of the support, and the latter will be thus securely and firmly held in place. The wire 7 may be engaged between the ear 90 13 and a binding screw or like part, but the wire is preferably secured to the terminal by placing the wire in the notch 12 and then placing solder 16 or like material within the opening 14 to secure the wire firmly in place. 95

In accordance with the provisions of the patent statutes, I have described the principles of operation of my invention, together with the device which I now consider to represent the best embodiment thereof; but 100 I desire to have it understood that the de-

vice shown is only illustrative, and that the invention may be carried out by other means.

I claim—

1. An electrical conductor including an insulation of soft, flexible material, a conducting core within said material, and a terminal comprising a tubular support having means to cut its way into said material and embedded therein, said material being located inside and outside of said support and exerting a grip thereon to retain it in place, and means to receive a connection.

2. An electrical conductor including an insulation of soft, flexible material, a core within said material, and a terminal comprising a tubular support having means to permit it to penetrate said insulating material, said material being located inside and outside of said support and exerting a grip thereon to retain it in place, said terminal also having means to receive a connection.

3. An electrical conductor including an insulation of soft flexible material, a core within said material, a terminal comprising a support of tubular shape larger than said core and having means to permit it to penetrate said material, the latter being located both within and without the terminal and exerting a grip thereon sufficient to retain it in place, and means on said terminal to receive an electrical connection.

4. An electrical conductor including an insulation of soft flexible material, a core with-

in said material, a terminal comprising a tubular support enough larger than said core to permit the location of the insulation between said core and said support, the latter having means to permit it to be embedded in said material that is located both within and without the support, and an ear extending from said support and having an opening to receive an electrical connection, said ear being electrically connected with said core.

5. An electrical conductor including an insulation of soft flexible material, a core within said material, a terminal comprising a tubular support having means to cut its way into said material, the latter being located both within and without the support and between it and said core, and a flat ear integrally formed with said support and having a lengthwise opening to receive a binding post and within which said core projects.

6. An electrical conductor including an insulation of soft flexible material, a core within said material, a terminal comprising a tubular support having means to cut its way into said material, the latter being located both within and without the support and between it and said core, means upon said support to cause it to enter said material, and a flat ear integrally formed with said support and having a lengthwise opening to receive a binding post and within which said core projects.

ELMER B. STONE.
